UNITED STATES PATENT OFFICE.

HARVEY JAMES DE FOREST, OF PORTLAND, MAINE, ASSIGNOR TO DE FOREST PRODUCTS COMPANY, OF PORTLAND, MAINE, A CORPORATION OF MAINE.

RUG BUILDER.

Application filed August 4, 1922. Serial No. 579,694.

To all whom it may concern:

Be it known that I, HARVEY JAMES DE FOREST, a citizen of the United States, and a resident of Portland, in the county of 5 Cumberland and State of Maine, have invented certain new and useful Improvements in Rug Builders, of which the following is a specification.

This invention relates to a device for 10 producing a design upon carpets or the like.

The primary object of my invention is to produce a device of the character described which will, through suitable mechanism, 15 produce a design by means of upstanding loops on any desired material, but preferably a material having a comparatively large mesh.

In accomplishing this result I work upon the reverse side of the material, producing 20 the desired loops upon the other side, so that when the material is turned over the design is apparent, and due to the upstanding loops a wear resisting carpet or rug has been produced which is extremely pleasing to the eye.

Another object of my invention is to provide means whereby the loops produced will be of a substantially equal height throughout the design.

30 Still another and important object is the provision of means for preventing the thread which is used to form the design from becoming tangled from the point of feeding to the point of engagement with the needle.

Still another object is the provision of an entire device which will be self-contained, light, strong and compact, which will require the least amount of effort to operate, 40 and which will be positive in its operation.

These objects I accomplish by providing a device including a frame upon which is mounted the operating motor which actuates through suitable gears and the like a 45 reciprocating needle, the same motor also actuating in a reciprocal manner what I term a retainer which moves in proximity to the needle but in a reverse manner. By means of these instrumentalities a loop is produced on the reverse side of the material by a complete reciprocation of the needle, upon which action the retainer is forced down between the mesh of the cloth to the bottom of the loop, and holds the same 50 while the needle moves upwardly, for-

wardly and downwardly through the material to make a second loop. At the end of its downward movement the retainer makes another reciprocation from the bottom of the loop which it is holding up through the 60 cloth and down again beside the needle to a point equal to the length of the previously formed loop and the cycle then repeated.

I have illustrated certain instrumentalities whereby the above objects are accomplished, but it is to be understood that I do not wish to be limited to the particular combination and construction and arrangement of parts illustrated, as obviously modifications will occur to those skilled in the 70 art which may accomplish the desired results. I have shown in the drawings the most preferred embodiment of which I am now aware, but this has been illustrated to clearly illustrate the specification. 75

In the drawings:

Figure 1 is a side elevation of one form of my device.

Fig. 2 is a view along line 2—2 of Fig. 1.

Fig. 3 is a plan view showing motor removed.

Fig. 4 is a view along lines 4—4 of Fig. 1.

Fig. 5 is a detail of the cam and associated mechanism.

Fig. 6 is a detail of the needle tube and 85 needle.

Referring now more particularly to these drawings, I provide a frame 1 upon which is suitably mounted a motor 2 electrically connected to a suitable source of energy and having a rotatable shaft 3 supported in bearing 4 and provided at its end with a gear 5. Journaled within the frame 1 at the side thereof is an actuating gear 6 engaging the small gear 5 and which is provided with 90 projections 7 for a purpose more fully hereinafter described. Suitably mounted upon the axis of the gear 6 is a member 8 having a cam surface 9 and provided with a pin 10 serving as an axis for a link 11. In the extremity of the cam portion 9 I provide a pin 12 movable through the member 8 so that it may project on either side of the member 8, as desired. One extremity of the pin 12 is provided with a circumferential recess 13 95 which is engaged by a spring 14 secured to the member 8, as at 15.

Vertically mounted within the frame 1 is a needle tube 16 mounted for rotation in the frame and having secured thereto collars 17. 110

The link 11 is provided with an annular member 18 encircling the needle tube 16 between the collars 17. A horizontal portion engaging the link 11 is secured thereto as by nut 19. It will thus be seen that link 11 is freely rotatable with the member 8. At the same time the needle tube 16 is rotatably held by the member 18.

A handle 20 pivoted to the frame as shown in Figs. 1 and 2 is provided with an angular portion engaging a bearing member in the frame, and is provided beyond this part with a substantially right angular portion of tapered form. The pin 12 under action of the spring 14 tends to be projected on the side of the cam 9 nearest the gear 6. While in this position the pin 7 on the gear 6 will engage the pin 12 to cause rotation of the mechanism. When it is desired, however, to stop the mechanism from rotating it is merely necessary for the handle 20 to be moved so that the tapered end which extends between the cam 9 and the gear 6 enters between the end of the pin 12 and the gear 6, with the result that the pin 12 is retracted against the tension of the spring 14.

It is noted particularly in Fig. 1 that there is a sufficient extent of that portion of the handle within the bearing to permit a certain axial movement in relation to the bearing which is sufficient to retract the pin 12 far enough to clear the pin 7. The weight of the handle 20 serves to keep the tapered portion in the position which will prevent the pin 12 from being projected to make contact with the pin 7, but when the handle 20 is lifted the natural tension of the spring 14 will project the pin outwardly to engage the pin 7.

Encircling the lower portion of the needle tube 16 is a retainer lifter 21 which is provided at its upper portion with an outwardly flanged integral cap 22 and at its lower portion with a ring 23 to which is hinged the retainer arm 24 having attached at its lower end the retainer proper 25, the function of which will be later described. A bearing 26 suitably attached to the frame 1 is provided for the retainer lifter 21. A knurled disc 27 is provided encircling the retainer lifter in order to rotate the same and the needle tube as desired, and a pin 28 extending horizontally from the disc 27 through slot 28a in the retainer lifter into a slot in the needle tube secures these members together and insures simultaneous rotation of these parts. This pin 28 allows independent vertical movement of the needle tube 16 and the retainer lifter 21, but upon rotation of the disc 27 these parts rotate together.

Attached to the side of the frame 1 below the actuating gear 6 is an elongated socket 29 within which is a reciprocable pin 30 which is located beneath the part 8 but off

center therefrom. The lowermost end of the pin 30 is in proximity to a lever 31 fulcrumed at 32 in a support 33 mounted upon the frame, the lever 31 having a semi-circular portion 34 with in-turned ends 35 70 engaging beneath the collar 22 of the retainer lifter, and which moves the same vertically when the pin 30 is moved downwardly against the upper portion of the lever 31.

The material with which the design is to be worked is indicated at 36 coming from any suitable source and located when passing through the mechanism inside of the needle tube 16 which prevents the material 80 from becoming soiled or tangled by contact with any moving parts. This material 36 exits from the lower portion of the needle tube 16 and is threaded through an angular eye 37 in the needle 38, said needle being attached to the lower extremity of the needle tube, as at 39. The needle is longitudinally grooved as at 40 and 41, the groove 40 being of a greater depth than the groove 41 for a purpose specified hereafter. 90

The frame 1 is provided with an extension 42 attached to a circular part 43 which rests upon the goods being worked, the portions 42 being provided with hand grips 44 which the operator grasps as he moves the entire device over the goods. A plate 45 encircling the retainer lifter 21 bears against the retainer ring 23 under action of the springs 46 attached to the plate and the extension 42. 100

The operation of the device is as follows:

The motor 2 is started which causes the free rotation of the actuating gear 6 on its axis. The handle 20 is now moved to cause the movable pin 12 to project from the gear side of the member 8 and upon such action one of the projections 7 engages the pin 12 which causes rotation of the member 8. This rotation causes through the link 11 a reciprocal movement of the needle tube 16 and attached needle, which gives the desired stitching effect. 105

As the part 8 rotates, the cam portion 9 engages the reciprocal part 30, causing the depression of the upper part of the lever 31, which in turn causes upward movement of the retainer lifter 21 because of the engagement of the in-turned ends 35 with the collar 22. Such action causes an upward movement of the retainer proper 25. 115

It will thus be seen that the rotation of the member 8 causes opposite movement of the retainer and the needle and when the former is in its extreme upward position the needle is in its extreme downward position. 120

As the part 8 revolves the needle is driven down through the material being worked, and as it reaches the bottom of its stroke the cam portion 9 engaging the pin 30 causes an upward movement of the retainer, which

moves to its extreme height, and as soon as it clears the top of the cloth it is swung against the needle under action of the spring 47 and then downwardly alongside the 5 needle under action of the springs 46. The retainer remains in this position holding the material carried through the work by the needle, while the needle arises and falls again a short distance away to form a new 10 loop. It will thus be seen that the retainer prevents losing the loop already formed while the needle is making a new one. It will be apparent that the retainer performs all of its up and down movement during the 15 period in which the needle is ceasing to go downward and preparing to move upward. In this way, the loop is of uniform length and shape.

The distance between loops is entirely governed 20 by the pushing movement of the operator in moving the machine over the stationary surface of the material being worked. Since the retainer 25 should always be in the rear of the needle; according to the direction 25 in which the machine is moving, rotation of the disc 27 will cause a like rotation of the needle and retainer, thus insuring the proper relation between these parts without rotating the entire mechanism. In this 30 way the sinuosities of a design may be readily followed.

The grooved needle allows the thread which may be of a comparatively large size and made of wool, stripped rags, waste, or 35 any other material, in flat, folded, round, or any other form, to lie close to the needle, thus reducing the friction as the needle reciprocates through the goods.

What I claim is:

1. A device of the type described including a frame adapted to rest upon and move over the goods being worked, freely rotatable needle carrying mechanism carried by said frame and means also carried by said frame for reciprocating said mechanism. 40

2. The device of claim 1, said needle carrying mechanism including a tube, said needle being secured thereto.

3. The device of claim 1, with a thread retainer cooperating with said needle to form 50 loops in the goods upon which the device operates, means to reciprocate said thread retainer, said means including a tubular element surrounding the needle carrying mechanism and means for reciprocating said 55 thread retainer out of time with said needle carrying mechanism.

4. The device of claim 1, said needle carrying mechanism reciprocating means including a rotatable cam, a retractable pin 60 therein adapted to engage means to cause rotation of said cam when the pin is in one position, and means connecting said cam and said needle carrying mechanism, said needle carrying mechanism being mounted therein 65 in a rotatable manner.

5. The device of claim 1, with a thread retainer cooperating with said needle to hold the loops formed in the goods worked upon, and means to freely rotate said needle carrying mechanism and said thread retainer simultaneously. 70

In testimony whereof, I affix my signature.

HARVEY JAMES DE FOREST.
